UNITED STATES PATENT OFFICE.

WALTER KNOWLES TROTMAN, OF WOOD GREEN, ENGLAND.

WATERMARKING OF PAPER.

No. 821,206.

Specification of Letters Patent.

Patented May 22, 1906.

Application filed October 5, 1905. Serial No. 281,442.

To all whom it may concern:

Be it known that I, WALTER KNOWLES TROTMAN, a subject of the King of England, residing at Wood Green, London, England, have invented certain new and useful Improvements in or Relating to the Watermarking of Paper, of which the following is a specification.

This invention relates to the watermarking of paper, and is more especially concerned with the rolls, usually the dandy-rolls, used for that purpose.

I will here describe a dandy-roll of my improved construction. According to present practice it is customary when a new watermark has to be made to provide an entirely new dandy-roll at considerable expense. By my invention I avoid the necessity for this.

In carrying out my invention I construct the cylindrical portion of the roll and its covering much according to present practice; but instead of making these parts continuous throughout the whole of the roll I make them in sections, some of which are movable. This may be carried out in the following manner: The ordinary practice in making rolls of this description is to have a hollow shaft or spindle upon which are a series of circular open disks. Upon these lies the cylindrical outer portion of the roll, constructed usually of longitudinal wires or rods upon which is wound a length of wire with spaces between the convolutions, this circumferential wire being soldered, sewed, or otherwise secured to the longitudinal rods. This cylindrical "back-sheet," as it is called, is usually in a single piece, and upon it is placed a wire-gauze sheet forming the outer surface of the roll, and upon this in the ordinary practice the device intended to produce the water-mark is dered or otherwise secured.

In my improved roll both the backsheet and the gauze covering are made with certain portions or sections removable. This may be managed in various ways; but conveniently the previously-mentioned longitudinal wires are interrupted in their length and secured to segmental pieces, preferably of metal and provided with hooked or other suitable slots or other fastening devices by which they can be secured in place in or upon the cylinder. The gauze covering is removably secured upon the section of the backsheet, so that it can be withdrawn and another section provided with the necessary

water-mark device substituted, after which the whole section is replaced in the roll.

Various means may be adopted for securing the covering upon the backing-sheet, a convenient method being to provide one edge of the gauze sheet with a longitudinal stiffener the ends of which fit into suitable slots in the ends of the segment of the backing-strip. The other end may be similarly constructed, preferably to fit into holes which may be advantageously square, or one end of the stiffener is secured by a spring or other suitable fastening.

In the accompanying drawings, Figure 1 is an elevation, partly in section, of one form of dandy-roll embodying this invention. Fig. 2 is a transverse section on the line 2 2 of Fig. 1; and Fig. 3 is an internal perspective view of a removable section of the roll.

Like letters indicate like parts throughout the drawings.

Upon a hollow shaft A is fixed a series of circular open disks B. To the periphery of these disks is attached the cylindrical frame of the roll, constructed of longitudinal rods C, upon which is wound a length of wire D, with spaces between the convolutions. This circumferential wire is soldered, sewed, or otherwise secured to the longitudinal rods C. Upon this cylindrical back-sheet of wire D is placed a wire-gauze sheet E; forming the outer surface of the roll.

In order to enable certain portions or sections of the roll to be removable, some of the longitudinal rods C are interrupted in their length and terminate at two disks B' B', between which a space is left round a part of the circumference of the roll. The section adapted to fill this space comprises the longitudinal bars C', secured to segmental pieces F and carrying the wires or backing-sheet D', upon which is placed the section of wire-gauze sheet E'.

The device intended to produce the watermark is soldered or otherwise secured to the section of gauze E'. The segmental pieces F are slotted at F' to engage pins B², projecting from the disks B', by which the removable section may be guided into its proper position in the roll. It will be understood that the removable sections are so constructed that they fit the roll exactly as though they actually formed an integral part thereof.

To fasten the removable section in or upon the cylinder, a short rod G is secured between

two of the segmental pieces F to act as a catch. A rotatable spindle H is supported in bearings H' on the hollow shaft A and extends right along inside the roll. This carries a hook H¹, preferably of slightly spiral form, which is arranged to engage the rod G when the removable section is placed in position and to exert an inward radial pressure upon the rod G when the spindle H is turned, so that the removable section is firmly held in position. The spindle H may be provided at the end with an arm or handle H³, arranged to be held in the gripping position by a spring-catch H⁴.

In the construction illustrated, particularly in Figs. 2 and 3, the gauze covering E' is removably secured upon the section of the backing-sheet D' as follows: One edge of the gauze sheet E' is provided with a longitudinal stiffener J, the ends of which fit into suitable slots F² in the segmental pieces F at the ends of the section. The other edge of the gauze sheet E' is provided with a stiffener K, one end K' of which is square and adapted to fit into a square hole F³ in one end segment F. At the other end of the stiffener K a sliding pin K² is arranged to pass through a hole F⁴ in the end segment and into a hole or tube K³ in the stiffener. To remove the wire gauze E' from the back-sheet D', the pin K² is shifted out of engagement with the holes K³ and F⁴, the stiffener K is released, and the stiffener J may then be removed from the slots F².

I have above described a method of carrying out my invention in conformity as nearly as possible with present practice. Nevertheless I wish it to be understood that I do not restrict myself to employing a separate backing-sheet and gauze covering for each section or for the whole roll, as these may be made or fixed permanently together as a single piece or section. Also I need not necessarily use wire-gauze at all, as other materials or things may be substituted for this purpose. Nevertheless usually some form of wire-gauze or equivalent is desirable, and I generally find it preferable to make it separate from the backing-sheet.

Although the previously-described open disks arranged upon a hollow shaft may, as stated, be used, I can dispense with both the hollow shaft and the perforated disks, relying upon longitudinal rods to give sufficient stability to the roll. In such case if I have to remove portions of the longitudinal rods to accommodate my removable sections any desired means of stiffening or strengthening the longitudinal wires at those parts, or altogether may be employed. The invention is equally

applicable to the flat frames such as are used in the manufacture of paper by hand.

What I claim as my invention, and desire to secure by Letters Patent, is—

1. A dandy-roll the cylindrical portion of which comprises a removable section carrying the watermarking devices for the purpose described.

2. In a dandy-roll the combination with the cylindrical portion of the roll having a space therein of a section of backing-sheet and a covering carrying a watermarking device both arranged to fit into the space for the purpose described.

3. In a dandy-roll the combination with the cylindrical portion of the roll having a space therein of a section of backing-sheet and a detachable gauze covering carrying a watermarking device both arranged to fit into the space for the purpose described. 80

4. In a dandy-roll the combination with the cylindrical portion of the roll of a removable section and means for securing such section in place.

5. In a dandy-roll the combination with the cylindrical portion of the roll of a removable section engaging with the roll and a hook rotatably mounted on the roll and arranged to secure the removable section in place.

6. In a dandy-roll the combination with the cylindrical portion of the roll of a removable section, a detachable gauze covering on such section, a watermarking device carried by said covering and stiffeners attached to the covering and adapted to engage with the 95 section.

7. In a dandy-roll the combination of a cylindrical portion consisting of gauze supported upon a frame formed by disks B longitudinal rods C and backing-sheet D and having a space therein, a removable section consisting of segmental pieces F, bars C', backing-sheet D' and gauze covering E' carrying a watermarking device, means for engaging the gauze covering E' with the removable 105 section and means for securing said section in place on the cylindrical portion substantially as described.

8. In an apparatus for watermarking paper, the combination with a wire frame having a space therein, of a removable section of the frame carrying the watermarking device for the purpose described.

In testimony whereof I have signed my name to this specification in the presence of 115 two subscribing witnesses.

WALTER KNOWLES TROTMAN.
